(57) **CLAIM**

The ornamental design for a motor car body with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front and right side perspective view of a motor car body with surface ornamentation showing our new design;

FIG. 2 is a front view thereof;

FIG. 3 is a right-side view thereof;

FIG. 4 is a rear view thereof;

FIG. 5 is a left-side view thereof;

FIG. 6 is a top plan view thereof; and,

FIG. 7 is a bottom view thereof.

Portions of the motor car body shown in broken lines illustrate a background and form no part of the claimed design.

The wheels shown in a faded out de-emphasized form and the portions of the motor car body shown in broken lines are all for illustrative and environmental purposes that form no part of the claimed design.
